UNITED STATES PATENT OFFICE.

GUSTAVE B. REISBACH, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,110,345.

Specification of Letters Patent.

Patented Sept. 15, 1914.

Application filed June 1, 1909. Serial No. 499,448.

To all whom it may concern:

Be it known that I, GUSTAVE B. REISBACH, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming a part of this specification.

My invention relates to electric switches and more particularly to those of the drum type.

One object of my invention is to provide a switch of simple and compact structure, having contacts thereon for reversing the circuit connections of an electric motor, and an auxiliary contact for controlling the continuity of the motor circuit.

A further object of my invention is to so arrange the auxiliary contact as to eliminate all danger of arcing between the same and the remaining contacts.

A still further object of my invention is to provide an auxiliary contact of a construction adapted to close one of two parallel circuits whereby limit switches may be used to stop the motor to prevent the operation of the mechanism driven thereby beyond its limits of travel.

Other objects and advantages of my invention will be hereinafter clearly set forth.

In the accompanying drawings, I have shown one of the forms which my invention may take.

In said drawings, Figure 1 is a front elevation of the reversing switch or drum controller with the cover removed; Fig. 2 is a transverse sectional view through the switch as seen on line 2-2, Fig. 1; and Fig. 3 is a diagrammatic view showing one circuit arrangement for the switch as applied to use.

In the embodiment of my invention illustrated, I provide an inclosing and supporting casing 2, preferably formed of two parts only, the back, top and bottom being formed in one piece, and the sides and front being formed in one piece. A shaft 3 is arranged to extend vertically through said casing, being supported in suitable journals 4 and 5, formed in the top and bottom respectively of the casing. The upper end of the shaft is extended beyond the top, to provide means to which a handle, or other device, may be

secured, by which the controller may be operated.

A drum preferably formed of two sections 6 and 7 is rigidly mounted upon the shaft. The lower ends of the drum sections 60 are secured by a suitable clamping member 8, fastened upon or formed integral with the shaft, by means of bolts 9 which extend through said clamping member and through downwardly extending lugs 10 on the drum sections. Suitable insulating disks 11 are interposed between the clamping member 8, the bolts 9 and the lugs 10 of the drum sections to effectually insulate the drum sections from each other and from the shaft. The upper ends of the drum sections are secured to the shaft in a different manner from that already described for the lower ends. An insulating disk 12 is secured near the upper end of the shaft in proximity to the ends of the drum sections, and the ends of said drum sections have outwardly extending portions 13 to which the disk is secured by means of screws or bolts 14. The drum sections carry suitable contacts 15 which are preferably secured upon projecting lugs 16, formed upon said drum sections. These contacts 15 are arranged upon the drum sections in the manner hereinafter set forth.

Mounted within the casing and secured to the back thereof is a base of insulating material 17, secured in position by any suitable means as by screws 18. The base 17 carries supports 19 for contact fingers 20. These contact fingers are preferably secured to the supports 19 by spring arms 21. The outer ends of the fingers 20 are arranged to engage certain of the contacts 15 on the drum sections, whereby electrical circuits are established. The supports 19 are provided with binding posts 22 by which the various conductors may be secured in electrical connection with the contact fingers 20.

Secured to the upper portion of the insulating disk 12 is a member 23. The member 23 is preferably formed with arms 24 extending to opposite sides of the shaft 3, and secured to the disk 12 in any preferred manner as by screws 25. Said member 23 is also provided with an upwardly and outwardly inclined portion 26 and a contact portion 27. The contact portion 27 is of less length than the contacts 15, for a purpose hereinafter set forth. Pairs of contact fingers 28 and 29, similar to the con-

5 contacts 20, are secured upon the insulating base 17 at its upper end in alinement with the contact fingers 20, and said contacts are adapted to be engaged by the contact portion 27, which is made wide enough to engage both fingers 28 or 29. The member 23 has its contact portion 27 disposed a considerable distance from the drum contacts and separated therefrom by the insulating disk for a purpose hereinafter set forth.

10 In Fig. 3, I have shown a diagrammatic view of one circuit arrangement for my device as applied to use. It will be understood that in the structure shown in Figs. 1 and 2, the sections 6 and 7 of the drum act as a conductor between the various contacts secured thereon. In the diagrammatic view, however, I have illustrated the various 15 contacts as being connected by conductors. I have also shown the use of limit switches and circuit controlling switches, the functions of which will be hereinafter explained. I will use exponents to distinguish the 20 various contacts on the drum as well as to distinguish the various contact fingers. The contacts on one section of the drum comprise two contacts 15^a and 15^b, and the contacts on the other section comprise contacts 25 15^c and 15^d. In the structure provided for operating a single motor, three contact fingers 20^a, 20^b and 20^c are provided upon one side of the base, and contact fingers 20^d, 20^e and 20^f on the other side. Above the 30 drum sections, I have provided contact fingers 28^a and 28^b on one side of the base, and contact fingers 29^a and 29^b on the other side thereof. The contact finger 20^a is connected by conductor 32 to the series field 33 of the motor, the series field being connected by conductor 34 to one terminal of an 35 electromagnetically controlled main switch 35. The other terminal of the main switch 35 is connected by conductor 36 to the positive side of the line. The shunt field 37 of the motor is connected to the conductor 32 and by conductor 38 to the negative side of the line. The contact finger 20^b is connected by conductor 39 to 40 contact finger 20^e, and by conductor 40 to the armature 41 of the motor, the other terminal of the armature being connected by conductor 42 to the contact finger 20^f. Contact fingers 20^c and 20^d are connected by conductor 43. Contact finger 20^d is connected by conductor 44 to the resistance sections of an automatic rheostat 45, the movable element of the rheostat being connected to the negative side of the line. Contact fingers 28^b and 29^b are connected by conductor 46, and contact finger 29^b is connected by conductor 47 to one terminal of the winding of the main switch 35, the other terminal thereof being connected to conductor 38. Contact fingers 28^a and 29^a are

50 connected by conductors 48 and 49 to one terminal of limit switches 50 and 51 respectively, the other terminals of said limit switches being connected by conductor 52 to the positive side of the line. One terminal of the winding of the automatic rheostat 45 is connected to a contact 53, adapted to be engaged by an auxiliary contact 54 on the main switch, when the main switch is closed, the other terminal thereof 55 being connected to the negative side of the line.

55 In operation, assuming that the drum is moved to the left, the contacts 15^a and 15^b will engage the contact fingers 20^a and 20^c respectively, and the contacts 15^c and 15^d will engage the contact fingers 20^d and 20^e respectively, thus connecting the motor field and armature in one relation. After these contacts are engaged, the contact portion 27, which, as before mentioned, is of less length than the drum contacts, will engage the contact fingers 28^a and 28^b, thus completing the circuit of the winding of the main switch 35. The main switch will 60 close, completing the motor circuit from the positive line, by conductor 36, across main switch 35, by conductor 34 through the series field 33, by conductor 32 to contact finger 20^a, contacts 15^a and 15^b, contact finger 20^c, conductors 43 and 42 to armature 41, and by conductor 40 to contact finger 20^b, conductor 39, contacts 15^c and 15^d, to contact finger 20^d, conductor 44, to and through the resistance sections of 65 the automatic rheostat 45 and its movable element to the negative side of the line. When the main switch closes, the circuit of the winding of the automatic rheostat 45 is also closed from the positive line by conductor 36, auxiliary contact 54, contact 53 through the winding to the negative side of the line. The rheostat will, therefore, 70 operate to remove the resistance from the motor circuit and bring the same up to 75 normal speed.

75 The motor will continue to operate until the operator moves the controlling switch to its initial position, causing the deenergization of the main switch and the opening of the motor circuit, or until one of the limit switches 50 or 51 is opened by the device operated as hereinafter more clearly set forth. Rotation of the drum in the opposite direction from initial position, causes contacts 15^a and 15^b to engage contact fingers 20^d and 20^e respectively, while the contacts 15^c and 15^d engage contact fingers 20^a and 20^b respectively. The contact portion 27 engages the contacts 29^a and 29^b and causes the main switch to close. This reverses the flow of current through the armature without changing the flow of current through the field, thus reversing the motor.

80 By utilizing a broad contact portion 27 85

of the construction described, which engages a pair of contacts, when the drum is moved in either direction, I am enabled to use limit switches in both of the parallel circuits controlled by said auxiliary contact, which will be automatically opened by suitable mechanism at the ends of travel of the device which may be operated by the motor. This is particularly desirable where the controller is used in elevator service, for, when the elevator reaches one limit of travel, one of the limit switches is opened, thus opening the circuit of the main switch. The motor will thus be automatically stopped, and it will be impossible to operate the controlling switch to close the main switch except by moving it in a direction to reverse the motor connections.

It will further be seen that the circuit arrangements of the motor are made by the controller, but that no circuits are broken at the controller, except the circuit of the winding of the main switch, which is broken by the large contact portion 27. Furthermore, by placing the member 23 on the insulating disk and forming the same as hereinbefore described, so that the contact portion 27 is a considerable distance from the drum sections, and separated therefrom by the insulating disk, there is no danger of arcing around said insulating disk between said auxiliary and reversing contacts.

I claim—

35 1. In an electric switch, in combination, a member movable in opposite directions, reversing switch contacts thereon, an insulating disk mounted on said movable member, an auxiliary contact member secured on said insulating disk and arranged with its contact surface spaced from the insulating disk and said reversing switch contacts, said auxiliary contact member adapted to close one of two parallel circuits when said movable member is moved in either direction.

2. In an electric switch, in combination, a member movable in opposite directions, reversing switch contacts thereon, an insulating disk mounted on said movable member, an auxiliary contact member secured on said insulating disk and arranged with its contact surface spaced from the insulating disk and said reversing switch contacts, said auxiliary contact member adapted to close one of two parallel circuits after the reversing switch contacts have been operated.

3. In an electric switch, in combination, a frame, an insulating base in said frame, contact fingers arranged on said base, a drum rotatably mounted in said frame, having reversing switch contacts thereon, coöperating with certain of said contact fingers to vary the circuit connections of a motor, an insulating disk at one end of said drum,

an auxiliary contact member secured to said disk away from said drum and having its contact surface spaced from said disk, said auxiliary contact adapted to coöperate with certain of said contact fingers to close one of two parallel circuits after the reversing switch contacts have engaged their respective contact fingers.

4. In an electric switch, in combination, a frame, an insulating base in said frame, contact fingers arranged on said base, a shaft rotatably mounted in said frame, drum sections secured on said shaft, reversing switch contacts arranged on said drum sections and coöperating with certain of said contact fingers for varying the circuit connections of a motor, an insulating disk on said shaft adapted to support one end of said drum, an auxiliary contact member on said insulating disk away from said drum and having its contact surface spaced from said disk, said auxiliary contact portion adapted to engage certain of said contact fingers to complete one of two parallel circuits after the motor connections have been made.

5. In an electric switch, in combination, a member movable in opposite directions, reversing switch contacts thereon, an insulating disk mounted on said movable member, an auxiliary contact member secured on said insulating disk and arranged with its contact surface spaced from the insulating disk and said reversing switch contacts, said auxiliary contact being adapted to close one of two parallel circuits when moved in either direction.

6. In an electric switch, in combination, a member movable in opposite directions and having reversing switch contacts thereon, an insulating disk mounted on one end of said movable member, an auxiliary contact member secured on said disk away from said movable member and arranged with its contact surface spaced from the insulating disk, said auxiliary contact being arranged to engage and disengage its coöperating contacts in inverse order to said reversing switch contacts.

7. In an electric switch, in combination, a frame, a shaft rotatably mounted therein, drum sections mounted on said shaft and insulated therefrom and from each other, reversing switch contacts on said drum sections, an insulating disk arranged on said shaft at one end of said drum sections, an auxiliary contact member on said insulating disk and having its contact surface spaced from said disk and said drum sections, said contact surface being of less length than said reversing switch contacts.

8. In a motor controlling device, in combination, a member movable in opposite directions, reversing switch contacts thereon, an auxiliary switch contact insulated from

said movable member and said reversing switch contacts, said auxiliary switch contact adapted to close one of two parallel circuits after the reversing switch contacts have been operated and limit switches arranged in said parallel circuits.

9. In a motor controlling device, in combination, a rotatable shaft, a drum on said shaft movable in opposite directions and having reversing switch contacts thereon, an insulating disk on said shaft, an auxiliary contact member on said insulating disk, and having its contact surface spaced from said disk, contact fingers arranged to be engaged by said reversing and auxiliary switch contacts, said auxiliary switch contact adapted to engage a pair of contact fingers to close one of two parallel circuits after said reversing switch contacts have engaged their respective contact fingers, and limit switches arranged in said parallel circuits.

10. In a motor controlling device, in combination, a frame, an insulating base in said frame, contact fingers arranged on said

base, a shaft rotatably mounted in said frame, a drum secured on said shaft, reversing switch contacts arranged on said drum and coöperating with certain of said contact fingers for varying the circuit connections of a motor, an insulating disk on said shaft adapted to support one end of said drum, an auxiliary contact member on said insulating disk away from said drum and having its contact surface spaced from said disk, said auxiliary contact portion adapted to engage a pair of contact fingers to complete one of two parallel circuits after the motor connections have been made, and limit switches arranged in said parallel circuits.

In witness whereof, I have hereunto subscribed my name in the presence of two witnesses.

GUSTAVE B. REISBACH.
